UNITED STATES PATENT OFFICE

FRANK FISCHER, OF LARCHMONT, AND GUDMUND SIVERTSEN, OF BROOKLYN, NEW YORK, ASSIGNORS TO GRANT OIL BURNER CORPORATION OF DELAWARE, OF NEW YORK, N. Y.

PUMP FOR OIL BURNERS

Application filed March 21, 1927. Serial No. 177,070.

This invention relates to rotary pumps of the gear type, and pertains to a particular unit construction whereby several sets of gears are assembled in a sectional housing 5 having passages and valves conveniently arranged to combine the pumping duties of the several pumps to the best advantage for oil-burner service.

One object of our invention is to provide 10 dual adjusting means; one for adapting the same unit to different furnaces of widely varying capacities; and the other for making the more minute adjustments to the particular furnace involved.

Another object is to avoid small restricted 15 passages likely to clog.

Another object is to cheapen the construction of the several pumps by combining them into a specially designed unit.

Another object is to facilitate accuracy of 20 construction.

These and other objects are attained by the combination of parts illustrated in the accompanying drawings in which—

Fig. 1 is a longitudinal vertical section of 25 our pumping unit, showing the motor direct-connected through a flexible coupling.

Fig. 2 is a transverse section taken on line AA of Fig. 1, showing the supply-pump 30 gears.

Fig. 3 is a transverse section taken on line BB of Fig. 1, showing the air-pump.

Referring now to the drawings in detail: 35 1 is the out-board end-section of the pump casing, containing the oil-strainer 2 which is open at the lower end and carried by the plug 3, as indicated. For convenience, the alternate sections of the pump casing will be referred to as disc-sections and housing-sections, the housing-sections surrounding the faces of the gears and the disc-sections enclosing the sides thereof.

4 is a pipe nipple connecting with the strainer cavity at its upper end, and with the oil-supply pipe at its lower end. The supply-pipe connects with the oil storage reservoir, not shown in the drawings.

5 is a nut for holding the pump unit tightly 45 to the hollow base 6. The interior of base 6

forms a reservoir or sump 7 for catching any surplus oil which is not fed to the burner.

8 is a hole through which oil passes from the strainer to the inlet of the supply-pump composed of gears 9 and 10 in housing-section 11.

Disc-section 12 contains drilled passage 13 for conveying the discharged oil from the supply-pump gears 9 and 10 to the elbow 14.

15 is an adjustable needle which forms a 50 needle-valve 16 with the discharge-end of elbow 14. Valve 16 may throttle but cannot entirely close, the passage of oil upward into sump 7.

17 is a drilled hole forming a branch passage 55 from discharge passage 13 to the lower side of another needle-valve 18 carried in disc-section 12.

19 represents a drilled hole or passage for 60 conveying the discharge from needle-valve 18 into the corresponding hole 20 formed in housing-section 21.

Housing-section 21 forms the casing of the air-pump (or air and oil mixing-pump), 65 which pump has a pair of two-teeth gears or 70 impellers 22 and 23, of the Root blower type.

In the lower central part of section 21 is formed the outer wall of an annular chamber 24 connecting with hole 20. The inner wall 75 is formed by nipple 26.

Passing through the center of annular chamber 24 is air intake passage 25 formed in nipple 26, connecting with the upper interior of sump 7. Sump 7 receives its air supply through suction ports 27.

Disc-section 28 contains discharge passage 29 and discharge nipple 30 for conveying 80 surplus oil from the sump 7 back to the storage reservoir. The storage reservoir and connecting pipe are not shown, but will be understood to connect with the lower end of nipple 30.

31 is another nut similar to 5 for holding 85 the combination pump housing fast to the base 6.

Housing-section 32 contains return-pump gears 33 and 34 for pumping oil from sump 7 to the storage reservoir. Gear 34 is not shown in the drawing, but is located on shaft 90 100

40 and bears the same relation to gear 33 as gear 10 does to gear 9 in Fig. 2.

35 is the drive-end disc-section, having formed therein the return-pump suction passage 36, connecting with suction nipple 37 which extends to within a short distance of the bottom of sump 7.

Disc-section 35 also contains oil drain-passage 38 for conveying any oil leaking along the drive shaft 39, back to sump 7.

10 All of the above gears and impellers are mounted on the two parallel shafts 39 and 40—which shafts are supported in bearings formed in disc-sections 12, 28 and 35. Gears 15 9 and 33, and impeller 21 are mounted on shaft 39; and gears 10 and 34, and impeller 22 are mounted on shaft 40.

Drive shaft 39, being the only shaft to extend outside the housing construction, is provided with an oil-throwing collar 41, mounted 20 in a chamber 42 where shaft 39 extends through disc-section 35. This collar 41 is designed to throw any oil leaking outward along the shaft 39, into chamber 42, from 25 which it is drawn through drain passage 38 to sump 7.

Leading from the top of the air-pump housing-section 21 is an air discharge pipe 43 connecting with burner-nozzle 44.

30 All of the housing and disc-sections are held together by tie bolts 45.

Motor 46 is mounted on base 6 and, directly-connected through flexible coupling 47 to drive-shaft 39.

35 Obviously, a casing built as above, with alternate disc and housing-sections, presents a number of advantages. The housing-sections can be bored straight through and the exact width obtained by grinding the parallel sides to the proper thickness to fit the 40 ends of the gears snugly. In this way, the minimum running clearances for the gears, so essential for high efficiency in this type of pump, are readily obtained. This construction is both economical and precise, and 45 insures leak-proof joints between the sections of the casing.

The strainer, as assembled in the first disc-section, is readily removed for cleaning or 50 replacement.

The operation of our pump is as follows:—

Oil is entrained from the reservoir (not shown) through nipple 4, strainer 2 and suction passage 8 into housing section 11, by 55 means of supply-pump gears 9 and 10; and is discharged through passages 13 and 17 and holes 19 and 20 to the mixing-pump and the surplus oil through elbow 14 and needle-valve 16, into sump 7.

60 Needle valve 16, being partly closed, imposes a back pressure on the oil in passage 13, thereby forcing the portion of oil to be burned through passage 17, needle-valve 18, passages 19 and 20, to annular chamber 24.

65 The amount of oil reaching chamber 24 is ob-

viously controlled by the adjustment of needle-valve 18.

In the meantime, air is being entrained through inlet openings 27 in the upper part of sump 7, through entrance passage 25, to 70 the lower side of air-pump impellers 22 and 23 in housing 21.

As the oil in annular chamber 24 overflows the upper end of nipple 26, it is picked up by the incoming air and discharged 75 through pipe 43 and nozzle 44 into the furnace.

The surplus oil discharged through needle-valve 16 into sump 7, is entrained through suction nipple 37 and passages 36 by gears 33 and 34 of the return-pump; and is discharged through passage 29 and discharge nipple 30 back to the storage reservoir. This completes the cycle of oil and air through the 80 pump.

Without needle valve 16, it is obvious that the maximum amount of oil which could be delivered through passage 17 to the nozzle 44 (with needle-valve 18 wide open) would depend upon the back-pressure produced by the friction of the oil passing through elbow 14 into sump 7; and in order to increase the flow to the nozzle 44 it is necessary to increase the friction. This can readily be done in the construction shown by screwing down 85 on needle 15, which is so contrived that it may throttle the oil but may not completely close needle-valve 16.

90 Needle-valve 16 is thus used merely to adapt the pump to large or small furnaces; while needle-valve 18 is employed to make the more minute adjustments of the pump to the particular furnace in which it is installed.

In practice, needle-valve 16 is closed only 100 enough to by-pass the maximum amount of oil required for a given furnace, when needle-valve 18 is wide open. Then this maximum flow is reduced to normal requirements by a partial closing of needle-valve 18.

105 It is apparent that by means of these two valves, a minute adjustment of the oil delivered to the nozzle may be made, without throttling either valve to a small size orifice; and probability of stoppage is thereby avoided.

110 Having thus fully described our invention, what we claim is new, and desire to secure by Letters Patent, is as follows:—

115 1. In a pumping unit for oil burners, a sump, a pair of parallel shafts, a sectional casing consisting of alternately disposed housing-sections and disc-sections, the housing sections being open on both sides and the disc-sections abutting and closing the sides of the housing-sections, a pair of oil supply-pump gears, a pair of air-pump impellers, and a pair of oil return-pump gears mounted 120 on the shafts in the housing-sections, one of the disc-sections having formed therein a 125

130

discharge passage for conveying oil from the supply-pump gears to the impellers and a by-pass from the discharge-passage to the sump, and a conduit for conveying surplus oil from the sump to the return-pump.

2. In a pumping unit for burners, a sump, a sectional casing consisting of alternately disposed housing-sections and disc-sections, the housing-sections being open on both sides and the disc-sections abutting and closing the sides of the housing sections, a pair of fuel supply-pump gears, a pair of air-pump impellers, and a pair of fuel return-pump gears in the housing sections, a conduit for conveying surplus fuel from the sump to the return-pump gears, one of the disc-sections having formed therein a discharge-passage for conveying fuel from the supply-pump gears to the impellers and a by-pass from the discharge-passage to the sump, and throttling means at the discharge-end of the by-pass for creating a back pressure of fuel toward the impellers.

3. In a pumping unit for oil burners, a sump, a sectional casing consisting of alternately disposed housing-sections and disc-sections, the housing-sections being open on both sides and the disc-sections abutting and closing the sides of the housing-sections, a pair of oil supply-pump gears, a pair of air-pump impellers, and a pair of oil return-pump gears in the housing sections, a conduit for conveying surplus oil from the sump to the return-pump gears, one of the disc-sections having formed therein a discharge-passage for conveying oil from the supply-pump gears to the impellers and a by-pass from the discharge-passage to the sump, a control-valve in the discharge passage to control the amount of oil admitted to the impellers, and a throttle-valve at the discharge end of the by-pass to control the back pressure of oil against the control-valve.

4. In a pumping unit for burners, a sump having an air inlet opening formed therein, a casing, the casing having formed therein a casing, the casing having formed therein an air-pump compartment and a fuel supply-pump compartment and a fuel return-pump compartment with individual inlet and outlet passages for each compartment and a by-pass connecting the outlet of the supply-pump compartment to the inlet of the air-pump compartment, restricting means in the outlet from the supply-pump compartment, a conduit connecting the sump with the outlet of the supply-pump compartment, another conduit connecting the sump with the inlet to the air-pump, and a third conduit connecting the sump with the return-pump compartment so as to form a controlled passage for liquid-fuel from the supply-pump compartment to the air-pump compartment and another passage for surplus fuel from

the supply-pump compartment to the return-pump compartment.

5. In a pumping apparatus for oil burners, a source of oil supply, a surplus-oil sump having an air inlet opening formed therein, an air and oil mixing-pump mounted above the sump, a conduit connecting the mixing-pump with the sump so as to convey air from the sump to the mixing-pump when the pump is running and to convey oil drainage from the mixing-pump to the sump when the pump stops running, and oil return-pump for conveying the surplus oil from the sump to the source of supply, an oil supply-pump having an inlet communicating with the source of supply, and a branched conduit connecting the discharge of the supply-pump with both the mixing-pump and the sump, the said branched conduit being so disposed as to convey an adequate supply of oil to the mixing-pump and any surplus oil to the sump.

6. In a pumping apparatus for oil burners, a source of oil supply, a surplus-oil sump, a positive displacement air and oil-mixing-pump mounted above the sump, said mixing-pump having an air inlet opening formed therein, a conduit connecting the mixing-pump with the sump so as to convey oil drainage from the mixing-pump to the sump when the pump stops running, an oil return-pump for conveying surplus oil from the sump to the source of supply, an oil supply-pump having an inlet communicating with the source of supply, a three branched conduit for conveying oil from the supply-pump jointly to the mixing-pump and to the sump, and restrictive means in the conduit branch leading to the sump for increasing the flow of oil through the other conduit branch to the mixing-pump, and another discharge conduit for conveying air and oil mixture from the mixing-pump to the burner.

7. In a pumping apparatus for oil burners, a source of oil supply, a surplus-oil sump, a positive displacement air and oil mixing-pump mounted above the sump, said mixing-pump having an air inlet opening formed therein, a conduit connecting the mixing-pump with the sump so as to convey oil drainage from the mixing-pump to the sump when the pump stops running, an oil return-pump for conveying surplus oil from the sump to the source of supply, an oil supply-pump having an inlet communicating with the source of supply, a two branched discharge conduit for conveying oil from the supply-pump jointly to the mixing-pump and to the sump, and throttling means in both branches of the discharge conduit for controlling the amount of oil admitted to the mixing pump.

8. In a pumping apparatus for burners, a pump casing, the pump casing having a fuel supply-pump compartment and an air-pump compartment and a fuel return-pump compartment and a drainage compartment.

- formed therein, a pair of shafts rotatably mounted in the casing and extending to all of the three pump compartments, one of the shafts being entirely enclosed within the pump casing and the other shaft extending at the drive-end through the drainage compartment and the pump casing, the drainage compartment being adapted to intercept fuel leakage through the casing along said other shaft, a sump casing located beneath the pump casing, and having an air inlet opening formed therein, a conduit for conveying liquid fuel from the supply-pump compartment to the air-pump compartment, other conduits connecting each compartment with the sump casing so as to supply liquid fuel to the return-pump compartment and air to the air-pump compartment and to convey liquid fuel from the drainage compartment to the sump when the shafts are rotating, said conduits also serving to convey drainage from all the compartments when the shafts cease to rotate, and means for rotating both shafts.
9. In a pumping apparatus for oil burners, a source of oil supply, a burner nozzle, a sump having an air inlet opening formed therein, a casing mounted above the sump so as to drain into the sump, the casing having formed therein an air-pump compartment with an inlet communicating with the upper part of the sump and a discharge outlet, the casing having formed therein also an oil return-pump compartment with an outlet communicating with the source of supply and an inlet communicating with a predetermined level in the sump so as to convey any oil tending to rise above said level to the return-pump compartment, the casing having formed therein also an oil supply-pump compartment with an inlet communicating with the source of supply and an outlet communicating with the sump and a passage connecting the outlet of the supply-pump compartment with the inlet of the air-pump compartment, impelling means movably mounted in the compartments, and restricting means in said outlet from the supply-pump compartment communicating with the sump for creating a back pressure in the passage to induce a flow of oil to the air-pump compartment.
10. In a pumping unit for burners, a sump having an air inlet opening formed therein, a casing mounted above the sump so as to drain into the sump, the casing having formed therein an air-pump compartment with an inlet communicating with the upper part of the sump, the casing having formed therein also a fuel return-pump compartment with an inlet communicating with a predetermined level in the sump so as to convey any fuel tending to rise above said level to the return-pump compartment, the casing having formed therein also a fuel supply-pump compartment with a passage connect-

ing the outlet of the supply-pump compartment with the inlet of the air-pump compartment, throttling means in said passage, impelling means movably mounted in the compartments, and restricting means in the outlet from the supply-pump compartment for manually adjusting to a minimum the fluid pressure exerted against the throttling means so as to permit the maximum opening of the throttling means for a given flow of fuel.
